UNITED STATES PATENT OFFICE.

HERMAN SCHIELKE, OF CLEVELAND, OHIO, AND EDUARD STEINMANN,
OF DAVENPORT, IOWA.

CORN-PLANTER.

SPECIFICATION forming part of Letters Patent No. 784,353, dated March 7, 1905.

Application filed October 28, 1904. Serial No. 230,403.

To all whom it may concern:

Be it known that we, HERMAN SCHIELKE, of Cleveland, Cuyahoga county, Ohio, and EDUARD STEINMANN, of Davenport, Scott county, 5 Iowa, both citizens of the United States, have invented certain new and useful Improvements in Corn-Planters, of which the following is a full, clear, and exact description.

Our invention relates to corn-planters; and 10 its object is to dispense entirely with the necessity of wires and the devices thereon for actuating the seed-distributing mechanism of the hopper of the machine and to accomplish the same result by a simple mechanism which 15 is carried by and constitutes part of each machine, will accommodate itself to the nature of the ground upon which it operates, and can be depended upon to properly actuate the seed-distributing mechanism of the hopper 20 under all circumstances. This we accomplish by the means hereinafter fully described, and as particularly pointed out in the claims.

In the drawings, Figure 1 is a side elevation of our improved corn-planter with a portion of the pole in front and a portion of the spur-wheel in the rear broken away. Fig. 2 is a plan view of our invention, and Fig. 3 is a side view of the spur-wheel and its connections broken away from the machine. 30

Our invention is applied to a corn-planter comprising hoppers A A, supported by the usual runner-frame B and actuated by a transverse rock-shaft C, which connects and 35 simultaneously operates the corn-feeding devices of each hopper. The top of the machine comprises a longitudinally-elongated rectangular wheel-frame α , the forward ends of the sides of which extend in front of the forward 40 cross-bar thereof and are preferably bent downward and have their extremities pivotally connected to the apex of an inverted-V-shaped bridge α' , which connects the transverse rails of the hopper-frame B, substantially as shown. Slightly to the rear of the center of length of this wheel-frame α the side members thereof have suitable bearings secured thereto and depending therefrom, in

which the axle b of the supporting-wheels c is journalled.

We make no particular claim to any invention in the parts of the machine hereinbefore broadly alluded to, for it will be obvious that our improvements may be applied to said hereinbefore-mentioned parts whether constructed as shown in the drawings or otherwise.

In order to actuate the shaft C, we provide the same, either at one end or both ends thereof near the hoppers A, with a downwardly-extending arm d . This arm has its lower extremities connected by means of a longitudinally-disposed connecting-rod e with the longer downward-extending arm of a bell-crank D, which latter is pivotally connected 65 to a bracket E, secured to and depending from the sides of the frame α at points located slightly in front of the axle b of the supporting-frame. This bell-crank has its shorter rearwardly-extending horizontally-disposed 70 arm engaged by the stud f , projecting laterally from the adjacent faces of a disk F, secured on the ends of a transverse shaft G, which latter is journalled in hangers h , secured to and depending from the sides of the frame 75 α in front of the axle of the wheel-frame about as shown. Between the bearings h and the disks F the shaft G has sleeves H mounted thereon, and these sleeves have the forward ends of longitudinally-disposed reaches I secured in a suitable manner thereto. These reaches preferably consist of metal bars or tubes which are given a downward semicircular bend near their forward ends, so as to enable them to pass under the axle b and then 80 extend to about under the rear cross-bar of the wheel-frame α and have suitable bearings J secured to their rear extremities, in which the transverse connecting-shaft K is journalled. The ends of this shaft extend beyond journals J and have their extremities journalled in bearings j , secured to the rear end of longer branches of the L-frame k , which latter have their forward ends bent laterally toward and secured in suitable T-couplings l , mounted on 90 the reaches I at points midway between the

plane of the axle *b* and the shaft *K*. Between these bearings *J* and *J* the shaft *K* has mounted thereon a spur-wheel *M*, which latter consists of a suitable central boss and equidistant 5 spurs or pointed spokes *m* radiating therefrom, the periphery described by the extremities of which is of such a diameter as to enable the said spur-wheels to revolve in a plane below the wheel-frame *a*. The shaft *K* is 10 connected and imparts its motion to shaft *G* through the medium of sprockets and chain *L*, and we prefer to make both sprockets of the same diameter, so that shaft *G* and the disks *F* will make one revolution with every 15 revolution of the wheels *M*. This, though, is not essential, for it might be desired in order to effect the proper spacing of the seed to make shaft *G* revolve either faster or slower than shaft *K*, and consequently to differ the 20 sizes of the sprockets in such manner as to accomplish this result. Ordinarily the spur-wheels will support the weight of the reaches *I* and structure forming a part thereof. There 25 are times, however—as, for instance, when the spur-wheels come in contact with stones or other objects or when the machine is being drawn to or from the field—when it would be desirable to lift the said reaches and spur-wheels, so that the points of the latter would 30 be out of the ground. This we accomplish by a bell-crank *N*, pivotally connected to one side of the wheel-frame *a*, near the rear thereof, which has its lower end connected by a chain *O* to a sleeve *P* on shaft *K* and its upper end 35 connected by a longitudinally-extending rod *Q* to the hand-lever *R*, which latter is of the usual construction and is fulcrumed to the side of wheel-frame *a* and may be provided with a pawl that engages the segmental rack 40 *S*, also secured to frame *a*, to hold it in any position to which it may be adjusted by the operator.

In operation the spur-wheels are dragged 45 over the ground as the machine moves forward and by reason of the spurs entering the ground will positively revolve shaft *K* and transmit its revolution to the shaft *G* through the medium of the sprocket-wheels and chain. Shaft *G* will impart its motion to the bell- 50 crank *D*, and the latter through the medium of the rod *e* will impart motion to the rock-shaft *C* on the runner-frame to actuate the feeding devices connected with the hoppers at stated intervals. As the spur-wheels travel 55 over the field they are apt to become more or less clogged by the soil or by penetrating such objects as pieces of wood or sections of corn-stalk every now and then. It is desirable that the spur-wheels be freed from these obstacles, 60 and this we accomplish by the means of a **U**-shaped guard *T*, the ends of which are suitably secured in clips *s*, fastened, respectively, to the reach and the **L**-shaped branch about as shown. These guards are bent so as 65 to describe an evolute, and the legs thereof

are made to approach and brush against the spurs in such a manner that they sweep the dirt and debris that collect thereon from a point near the center of the wheel out off of their extremities as the spur-wheel revolves, substantially as shown in the drawings. 70

What we claim as new is—

1. In a check-rower planter, the combination with the hoppers, seed-feeding devices, supporting-frame and running-gear therefor, of 75 spur-wheels, shaft on which the same are mounted the axis of which is below said supporting-frame, and means for operatively connecting said shaft with said feeding devices.

2. In a check-rower planter, the combination with the hoppers, seed-feeding devices, supporting-frame and running-gear therefor, of a spur-wheel the axis of which is below said supporting-frame, and means for operatively connecting said spur-wheel with said feeding 80 devices.

3. In a check-rower planter, the combination with the hoppers, seed-feeding devices therefor, a rock-shaft for actuating the same, a supporting-frame, and running-gear thereof, of 90 a spur-wheel the axis of which is below said supporting-frame, and means for operatively connecting said spur-wheel to said rock-shaft.

4. In a check-rower planter, the combination with the hoppers, seed-feeding devices therefor, a rock-shaft for actuating the same, a supporting-frame, and running-gear thereof, of 95 spur-wheels, shaft on which the same are mounted the axis of which is below said supporting-frame, and means for operatively connecting said spur-wheel shaft to said rock-shaft. 100

5. In a check-rower planter, the combination with the hoppers, seed-feeding devices therefor, a supporting-frame, and the running-gear 105 thereof, of spur-wheels, shaft on which the same are mounted, the axis of which is below said supporting-frame, a frame in which said shaft is journaled which is pivotally connected to the said supporting-frame, and means for 110 operatively connecting the spur-wheel shaft to said feeding devices.

6. In a check-rower planter, the combination with the hoppers, seed-feeding devices therefor, a supporting-frame, and the running-gear 115 thereof, of a spur-wheel, a shaft therefor the axis of which is below said supporting-frame, and a guard for removing foreign matter therefrom, and means for operatively connecting said spur-wheels to said feeding devices. 120

7. In a check-rower planter, the combination with the hoppers, seed-feeding devices therefor, a supporting-frame and the running-gear thereof, of a spur-wheel, and a **U**-shaped guard 125 for removing foreign matter therefrom, and means for operatively connecting said spur-wheels to said feeding devices.

8. In a check-rower planter, the combination with the hoppers, seed-feeding device therefor, a supporting-frame, and the running-gear 130

- thereof, of a spur-wheel, and a U-shaped curved guard for removing foreign matter therefrom, and means for operatively connecting said spur-wheels to said feeding devices.
- 5 9. In a check-rower planter, the combination with the hoppers, seed-feeding devices therefor, a supporting-frame, and the running-gear thereof, of a spur-wheel, and a U-shaped evo-
lute curved guard for removing foreign matter therefrom, and means for operatively connecting said spur-wheels to said feeding devices.
- 10 10. In a check-rower planter, the combination with the hoppers, seed-feeding devices therefor, a rock-shaft for actuating the same, an arm projecting from said rock-shaft and bell-crank pivotally connected to a suitable supporting-frame, said supporting-frame, and the running-gear thereof, of spur-wheels, and a frame in which said spur-wheels are journaled which is pivotally connected to said supporting-frame, a transverse shaft, means on the end thereof engaging said bell-crank, and sprockets and chain for imparting the motion of said spur-wheels to said transverse shaft.
- 15 11. In a check-rower planter, the combination with the hoppers, seed-feeding devices therefor, a supporting-frame, and the running-gear thereof, of spur-wheels, a frame in which said spur-wheels are journaled, a transverse shaft pivotally connecting said spur-wheel frame to the supporting-frame, means for imparting the motion of said spur-wheels to said transverse shaft, and continuously-connected mechanism for operatively connecting said transverse shaft to said feeding devices.
- 20 12. A check-rower planter, the combination with the hoppers, seed-feeding devices therefor, a supporting-frame, and the running-gear thereof, of spur-wheels, a frame in which said spur-wheels are journaled the forward ends of which are pivotally connected to said supporting-frame, means for operatively imparting the motion of said spur-wheels to said feeding devices, and continuously-connected mechanism for raising and lowering said spur-wheel frame.
- 25 13. In a check-rower planter, the combination with the hoppers, seed-feeding devices therefor, a supporting-frame, and the running-gear thereof, of spur-wheels, a frame in which said spur-wheels are journaled, and guards on each side of said spur-wheels for removing foreign matter therefrom one end of which is secured to said spur-wheel frame, and means for operatively connecting said spur-wheels to said feeding devices.
- 30 14. In a check-rower planter, the combination with the hoppers, seed-feeding devices therefor, a supporting-frame, and the running-gear thereof, of spur-wheels, a frame in which said spur-wheels are journaled having the forward ends thereof pivotally connected to said supporting-frame, and U-shaped guards for removing foreign matter from said spur-wheels the ends of which are secured to said spur-wheel frame on the opposite sides of said wheel.
- 35 15. In a check-rower planter, the combination with the hoppers, seed-feeding devices therefor, a supporting-frame, and the running-gear thereof, of spur-wheels, a frame in which said spur-wheels are journaled, having the forward ends thereof pivotally connected to said supporting-frame, and U-shaped curved guards for removing foreign matter from said spur-wheels the ends of which are secured to said spur-wheel frame on the opposite sides of said wheel.
- 40 16. In a check-rower planter, the combination with the hoppers, seed-feeding devices therefor, a supporting-frame, and the running-gear thereof, of spur-wheels, a frame in which said spur-wheels are journaled having the forward ends thereof pivotally connected to said supporting-frame, and U-shaped guards for removing foreign matter from said spur-wheels the ends of which are secured to said spur-wheel frame on the opposite sides of said wheel.
- 45 17. In a check-rower planter, the combination with the hoppers, seed-feeding devices therefor, a supporting-frame, and the running-gear thereof, of spur-wheels, a frame in which said spur-wheels are journaled having the forward ends thereof pivotally connected to said supporting-frame, and a curved guard for removing foreign matter from said spur-wheel frame on the opposite sides of said wheel.
- 50 18. In a check-rower planter, the combination with the hoppers, seed-feeding devices therefor, a supporting-frame, and the running-gear thereof, of spur-wheels, a frame in which said spur-wheels are journaled the forward ends of which are pivotally connected to said supporting-frame, a bell-crank pivoted to the supporting-frame near its rear end, a chain connecting said bell-crank to the shaft of said spur-wheels, a hand-operated lever, and a connecting-rod connecting said lever and bell-crank, and continuously-connected means for operatively connecting said spur-wheels to said feeding devices.
- 55 In testimony whereof we have signed our names to this specification, this 29th day of September, 1904, in the presence of two subscribing witnesses.
